PROCESS FOR TREATING TOBACCO

Horace L. Smith, Jr., and Lucian N. Jones, Richmond, Va., assignors to Thermal Engineering Corporation, Richmond, Va., a corporation of Virginia

Application March 28, 1936, Serial No. 71,495

19 Claims. (Cl. 131—55)

This invention relates to a process for treating tobacco and more particularly concerns a process involving altering the moisture content of tobacco.

5 This application is a continuation in part of our copending application Serial No. 44,156 filed October 9, 1935 entitled "Process for treating tobacco" and of our copending application Serial No. 54,443, filed December 14, 1935, entitled 10 "Treatment of tobacco".

At various stages during the preparation and shipment of tobacco it is necessary to change its moisture content. Thus, for example, tobacco for export must have a specified minimum moisture content and any excess over this amount adds to the shipping cost and export duty thereon, while a deficiency in moisture subjects the shipper 15 to a penalty.

One of the most important operations in which 20 moisture is added to tobacco is that known in the art as "ordering". After tobacco leaves have been cut and flue or sun cured, they are tightly packed in hogsheads and aged in warehouses for several years. During aging, the tobacco becomes so dry and brittle that it cannot be stemmed or handled, in fact can not be taken from the hogsheads or otherwise disturbed, without shattering the leaves and rendering it unfit for use. The operation known as "ordering" is a moistening treatment designed to increase the moisture content of aged tobacco to a point where it can be 25 unpacked and stemmed without destructive shattering.

It has heretofore been the practice to moisten 30 tobacco for stemming and handling by first placing the hogsheads of dry aged tobacco in sweat rooms maintained at a temperature of about 110° F. and a relative humidity near the saturation point (say about 95%) for a period of several days. This increases the moisture content to an extent such that the tobacco can be unpacked 35 from the hogsheads without excessive breakage of the leaves although some loss results. The sweat room operation does not within a reasonable time supply sufficient moisture to permit the stemming of the tobacco leaves, and accordingly after the leaves are unpacked from the hogsheads they are steamed until the moisture content has increased to a value at which the stemming operation can be performed.

The above-described known tobacco moistening process requires the provision of large expensive sweat rooms and involves tying up considerable quantities of tobacco for extended periods. The known process entails a steaming operation after

the tobacco is unpacked and results in considerable handling of the tobacco leaves prior to stemming. Further, with this process, it is difficult to produce the exact final moisture content at which the leaves are best suited for stemming or other operations.

Packed tobacco is frequently found to be infested with worms or other organisms, such as the cigarette beetle or tobacco moth in various stages of the life cycle, and accordingly, must be 10 fumigated or otherwise treated prior to processing. This has in the past been accomplished by treating the tobacco with gases toxic to the organisms present, and the costs involved in fumigation of this type are considerable. Moreover, known fumigating processes, although in most cases effective in killing the worms or insects, frequently fail to kill the eggs from which the organisms develop.

With the above and other considerations in 20 mind, it is proposed in accordance with the present invention to provide an improved process for rapidly and inexpensively increasing the moisture content of tobacco accurately by any desired amount. Another object of the invention is the 25 provision of a process in which the moisture content of the tobacco can be raised to the exact point desired while the tobacco remains packed in the aging hogsheads, whereby shattering or other injury to the tobacco leaves due to repeated handling is avoided. A further object of the invention is the provision of a process for exterminating pests, such as the tobacco weevil or other 30 organisms found in tobacco, which process effectively kills the eggs of the organisms as well as 35 the worms or insects. Other objects and advantages of the process will become apparent from the appended detailed description.

In general, the process of the invention involves first subjecting tobacco to a high degree 40 of vacuum whereby a large proportion of the air contained in the structure is removed, then reducing the degree of vacuum while supplying to the tobacco an amount of steam somewhat in excess of that required to produce the desired final 45 moisture content, and then again increasing the vacuum on the tobacco whereby the excess moisture is evaporated and at least a part of the heat supplied by the steam is absorbed. The final step insures that immediately after the steam treatment, the tobacco is cooled to a safe temperature. The entire process can be completed in a matter of minutes and accordingly a large quantity of tobacco can be treated with comparatively 50 small and inexpensive apparatus. Our process is 55

applicable to tobacco in either the packed or the unpacked state, and by the use of the process the tobacco may remain undisturbed in aging hogsheads or other containers until it has been moistened to the exact degree at which the subsequent stemming or other operations can best be performed. In this manner, the process avoids shattering or other injury to the tobacco leaves due to handling when the moisture content is low.

If tobacco is maintained at temperatures above about 125° F. for extended periods, it becomes discolored and often moulded or rotted, probably due to the decomposition of oils or other substances in the leaves. However, tobacco will stand temperatures of 180° F. or even higher for periods of ten or fifteen minutes, and proportionately higher temperatures for shorter intervals without discoloration or other detrimental change. In our process, the steam introduced to moisten the tobacco increases the temperature thereof as it condenses on the leaves, but the moistening step of the process is very short, and immediately thereafter the entire mass of packed tobacco is rapidly cooled by vacuum evaporation of the excess moisture to a safe temperature. Thus with our process the moistening can be carried out very rapidly without injury to the tobacco and it is not necessary to unpack and cool the treated tobacco to prevent heat deterioration thereof. The final temperature of the tobacco after completion of our process may be varied as desired and is preferably well below 125° F., at which temperatures the tobacco can remain indefinitely without deterioration.

We have discovered that by the application of our vacuum process, organisms which infest tobacco, in the form of larvae, pupa or beetle, as well as the eggs of such organisms, may be killed. This may be accomplished as the result of the tobacco moistening process referred to above, or, if it is desired to exterminate the pests without altering the moisture content, this can be readily accomplished by continuing the final vacuum evaporation at a value of vacuum or for a time such that the moisture content of the tobacco is reduced to its initial value. The extermination of pests without substantial net change in the moisture content is particularly desirable when the tobacco is to be stored for extended periods after the extermination, since in such cases a high moisture content might result in moulding or other deterioration of the tobacco while in storage.

Various forms of apparatus may be employed in carrying out our process, and in the accompanying drawing, the single figure is a diagrammatic and simplified representation of one type of apparatus in which the new process can be performed.

Referring to the drawing, the apparatus there represented comprises generally a vacuum chamber or bell 1 removably mounted on a platform or base plate 2, together with means for evacuating the chamber and for admitting steam thereto. The vacuum chamber shown comprises a bell or inverted air tight chamber, the lower edges of which rest on a gasket 3 carried by the base plate 2. With this arrangement, the bell 1 may be readily lifted to permit the insertion and removal of tobacco. Two tobacco hogsheads 4 have been represented within the bell 1.

Low pressure steam may be applied to the interior of the bell 1 through a pipe 5 under the control of a valve 6. Suitable means may be

provided in the steam pipe 5 for measuring or metering the quantity of steam admitted to the vacuum bell during the process. Such a device has been diagrammatically represented at 7, and may comprise an orifice of suitable known dimensions or an integrating fluid meter. A gauge 8 may be provided for indicating the steam pressure in the pipe 5.

Suitable means are provided for controllably evacuating the bell 1. Although various forms of pumps or other suction devices may be used with good results, we have found that steam jet evacuators are admirably suited to our process. We have accordingly illustrated in the drawing a three-stage steam jet evacuator E having its intake connected to the vacuum or suction pipe 9 leading to the interior of the bell 1 through the plate 2. A control valve 18 is preferably provided in the suction pipe 9. The evacuator illustrated includes a first stage steam jet booster 10, an intercondenser 11, a second stage steam jet booster 12, a second intercondenser 19 and a third stage steam jet booster 20. The number of stages of evacuating boosters may be increased or decreased, and the invention is in no way limited to the use of the three-stage apparatus illustrated. Since multi-stage steam jet evacuators of the type illustrated are well known in the art, and since the invention is in no way limited to the use of the particular evacuator illustrated, a detailed description of the construction thereof will not be given.

The vacuum or absolute pressure within the bell 1 is indicated by a suitable gauge 14 and the temperature by a thermometer 15. Suitable means are provided for admitting air to break the vacuum within the bell 1, and, as shown, a pipe 16 passing through the base plate 2 and controlled by the valve 17 may be employed for this purpose.

The process of the invention may be employed to increase the moisture content at various stages during the preparation or shipment of tobacco, and is in no way limited to any particular phase of tobacco treatment. The process is particularly useful in connection with preparing aged and dry tobacco for unpacking and stemming, and accordingly will be described in this connection.

The aged tobacco, packed in hogsheads 4, is placed on the base plate 2 within the gasket 3 and the bell 1 is seated on the gasket over the hogsheads as shown in the drawing. The heads may be removed from the hogsheads before treatment if desired, but this operation is not essential since the hogsheads are not fluid tight. With the valves 6 and 17 closed and the valve 18 open, the evacuator E is operated until a high vacuum is produced. The tobacco is maintained under this high vacuum for a few minutes to permit substantially complete removal of air therefrom. With valves 17 and 18 still closed, a quantity of low pressure steam is admitted to the bell 1 from the pipe 5, the amount admitted being regulated by the valve 6. The initial inrush of the steam lowers the vacuum, and thereafter the condensation of the steam maintains the lower vacuum substantially constant.

Prior to the moistening treatment, the initial moisture content of the tobacco is determined in any suitable known manner. The amount of steam required to increase this initial moisture content to that desired is then calculated or determined by tests, and the amount of steam admitted to the bell 1 as described above is regulated to

exceed this required amount by a known margin. An appreciable excess of moisture is thus supplied, but the amount of the excess is not critical and may be varied in accordance with the total moisture required by the tobacco and other factors.

In applying the process to the moistening of aged tobacco, and considering a lot of tobacco having an initial moisture content of about 11% and a desired final moisture content of about 14%, the amount of steam admitted may be such as will supply an amount of moisture from 20% to 30% in excess of the quantity required to give the desired final moisture content.

During the admission of the steam, the vacuum on the tobacco is reduced, and at the same time, the tobacco is heated to a high temperature, well above 125° F., and which may be as high as 160° F. or even higher. If the tobacco were allowed to remain at such a high temperature for any considerable length of time, it would be discolored and otherwise deteriorated by the heat. According to the present process, however, the steaming process is immediately followed by a final vacuum evacuating stage which not only extracts the excess moisture present, but, also cools the tobacco by vacuum evaporation to a safe low temperature which is appreciably below 125° F.

When the predetermined amount of steam has been admitted, the valve 6 is closed, suction valve 18 is opened and the vacuum in the bell 1 is increased. This causes the rapid evaporation of the excess moisture from the tobacco and thus refrigerates and cools the tobacco due to the absorption of heat during the vacuum evaporation.

When the moisture content has been reduced to the desired final value, the temperature of the tobacco will have dropped to a safe low value, at this point the valve 18 is closed, and the vacuum is broken by opening the air valve 17, completing the process. The evaporating step is rapidly performed and in many cases may be completed in three or four minutes. After the vacuum is broken the bell 1 is removed from the base plate 2, the treated hogsheads are removed and other hogsheads for treatment are placed on the plate and processed as described above.

We have found that the degree of vacuum which should be employed in the initial evacuating stage of the process is somewhat dependent upon the temperature of the tobacco, and should, in general, be increased when the initial temperature of the tobacco is low. Under normal conditions, when the process is employed to a lot of tobacco, the mass of which has an initial minimum temperature of about 50° F., the initial high vacuum may be about 29.65 inches of mercury or slightly higher. When the tobacco is colder, higher values of vacuum must be used in the initial evacuating stage, and under extremely low temperature conditions, an initial vacuum of 29.85 inches of mercury or even higher may be necessary. It will be understood that where steam jet evacuators or boosters are used to produce the vacuum, the number of stages employed may be varied as required to economically obtain the necessary evacuation.

The point at which the vacuum is broken and the process terminated may be determined by the temperature within the vacuum bell 1 as indicated by the thermometer 15. The amount of excess moisture present, the degree of vacuum under which the final evaporation takes place and the initial temperature within the bell may be maintained at the same values during the treatment of successive lots of tobacco, and under these cir-

cumstances, when the moisture content is reduced to the desired point the temperature in the bell will reach a definite value which can be determined by calculation or test for any given set of conditions.

The value of vacuum employed in the final evacuating stage may be varied between wide limits in accordance with the amount of moisture added by the steaming operation and the final moisture content desired. In general, where moisture is to be added, the final increase of vacuum is not sufficient to bring the vacuum back to its initial height. When the process is employed for the extermination of pests and it is desired to restore the tobacco to its initial moisture content, the increase in vacuum employed in the final evaporating stage may be sufficient to reach the initial vacuum.

In applying our process to the extermination of pests, such as the cigarette beetle, the tobacco may be treated in the manner described above in connection with the addition of moisture. Thus the tobacco is successively subjected to an initial high vacuum, then to an application of steam under reduced vacuum whereby the tobacco temperature is raised to a value well above 130° F. and preferably in the neighborhood of 160° F. or higher, and finally subjected to a vacuum higher than the steaming vacuum and sufficient to lower the tobacco temperature to a value at which heat deterioration can not take place. The extermination of the pests may be accomplished concurrently with the addition of moisture to the tobacco, or, as explained above, the moisture content may be restored to its initial value so that after extermination the tobacco may be stored indefinitely without moulding or other deterioration due to excess moisture. The exterminating operation is very inexpensive and highly effective, killing not only the larvae, pupae and insects present, but also the eggs which are usually deposited in the tobacco structure.

Our process is carried out very rapidly and with a minimum amount of labor, the tobacco remaining undisturbed in the aging hogsheads until after the process has been completed. By employing an initial high vacuum and reducing this vacuum while treating the tobacco with the steam, the moistening operation can be completed in a few minutes. The introduction of excess moisture and its subsequent evaporation under vacuum reduces the temperature of the tobacco to a safe value long before any discoloration or other heat deterioration can take place. In carrying out the process as described above, the tobacco is subjected to temperatures in excess of 125° F. for a period of only a few minutes, and accordingly all danger of deterioration due to prolonged high temperatures is avoided.

It should be understood that the invention, in its broader aspects, is not limited to the particular values of temperature, pressure, time and moisture content set forth in the above described operation of the process. These values may be widely varied to suit the conditions of the particular lot of tobacco under treatment and the final moisture content or temperature desired.

We claim:

1. A process for moistening tobacco comprising first subjecting the tobacco to a relatively high vacuum, then supplying steam to the tobacco while reducing the vacuum thereon, and then as a final step subjecting the tobacco to an increased vacuum until it has been cooled by evaporation

- to a temperature at which discoloration cannot take place.
2. A process for increasing the moisture content of tobacco to a predetermined value which comprises subjecting the tobacco to a relatively high vacuum, supplying a predetermined amount of steam to the tobacco while maintaining the tobacco under lower vacuum, and then as a final step subjecting the tobacco to an increased vacuum until the moisture content thereof has been reduced by vacuum evaporation to the desired value, whereby some of the heat supplied to the tobacco by the steam is immediately absorbed by the evaporating moisture, and no perceptible change of color of the tobacco takes place.
3. A process for increasing the moisture content of tobacco to a predetermined value which comprises subjecting the tobacco to a relatively high vacuum, reducing the vacuum on the tobacco and supplying thereto, while under such lower vacuum, an amount of steam sufficient to supply moisture in an amount from 20% to 30% in excess of that necessary to produce the desired predetermined value, and then subjecting the tobacco to an increased vacuum until the temperature thereof has been lowered below that at which heat deterioration can take place and the excess moisture has been evaporated.
4. A process for increasing the moisture content of tobacco to a predetermined value which comprises subjecting the tobacco to a relatively high vacuum, reducing the vacuum on the tobacco and supplying thereto, while under such lower vacuum, an amount of steam sufficient to supply moisture in an amount from 20% to 30% in excess of that necessary to produce the desired predetermined value, and then maintaining the tobacco under vacuum of sufficient height that while the excess moisture is evaporated, the temperature of the tobacco will be lowered to a value below 125° F.
5. A process for increasing the moisture content of tobacco which comprises subjecting the tobacco to a high vacuum, maintaining the tobacco under lower vacuum while supplying thereto a quantity of steam sufficient to supply moisture in excess of the amount desired, and then subjecting the tobacco to high vacuum until the temperature of the tobacco has been lowered below that at which heat deterioration can take place by vacuum evaporation of the excess moisture.
6. A process for moistening tobacco to a predetermined degree which comprises subjecting the tobacco to an initial high vacuum, supplying steam to the tobacco while decreasing the degree of vacuum to which it is subjected, the total amount of steam so supplied being in excess to that required to bring the moisture content of the tobacco to the desired point, and then subjecting the tobacco to a vacuum higher than that obtaining while the steam was supplied thereto but appreciably lower than said initial high vacuum, whereby the excess moisture is evaporated and the tobacco is cooled, and no perceptible change of color of the tobacco takes place.
7. A process for increasing the moisture content of tobacco which comprises subjecting the tobacco to a high initial vacuum, maintaining the tobacco under lower vacuum while supplying thereto a quantity of steam sufficient to supply moisture in excess of the amount desired, and then subjecting the tobacco to a vacuum higher than that to which it was subjected while the steam was supplied thereto but appreciably low-
- er than said high initial vacuum until the temperature of the tobacco has been lowered by vacuum evaporation of the excess moisture to a value at which heat deterioration cannot take place.
8. A process for moistening tobacco comprising successively subjecting the tobacco to a high vacuum, supplying steam to the tobacco while reducing the vacuum thereon and then as a final step increasing the vacuum to a value sufficient to cause evaporation of at least some of the moisture supplied to the tobacco by the steam, whereby no perceptible change of color of the tobacco takes place.
9. A process for exterminating organisms in tobacco comprising subjecting the tobacco to a high vacuum, simultaneously supplying steam to the tobacco and reducing the vacuum thereon whereby the tobacco is heated, and then as a final step increasing the vacuum on the tobacco until the tobacco temperature is reduced to a value below that at which heat deterioration takes place.
10. A process for exterminating organisms in tobacco comprising subjecting the tobacco to a high vacuum, supplying steam to the tobacco while reducing the vacuum thereon whereby the tobacco is heated to a temperature at which heat deterioration would take place after a time interval, and, as a final step prior to the expiration of such interval, increasing the vacuum on the tobacco to a value such that its temperature is reduced below that at which heat deterioration takes place.
11. A process for increasing the moisture content of tobacco by a predetermined amount which comprises first subjecting the tobacco to a vacuum from 28 to 29½ inches of mercury, then reducing the vacuum by 8 to 10 inches of mercury and maintaining the vacuum at such intermediate value while supplying to the tobacco an amount of steam sufficient to increase the moisture content of the tobacco by an amount from 20% to 30% in excess of the increase desired, and then subjecting the tobacco to an increased vacuum of from 28 to 29½ inches of mercury until the excess moisture is evaporated and the temperature of the tobacco is reduced below 120° F.
12. A process for moistening tobacco comprising subjecting the tobacco to a high vacuum, then supplying steam to the tobacco to reduce the vacuum thereon, the tobacco being maintained at sub-atmospheric pressure while the steam is so applied, and then as a final step increasing the vacuum on the tobacco sufficiently to cause evaporation of some of the moisture supplied to the tobacco by the steam, whereby no perceptible change of color of the tobacco takes place, the tobacco being maintained at sub-atmospheric pressure throughout the process.
13. A process for moistening a mass of tobacco comprising subjecting the tobacco to a high vacuum, then supplying steam to the tobacco while reducing the vacuum thereon to a sub-atmospheric pressure sufficiently in excess of the initial high vacuum to cause penetration of the steam throughout the tobacco mass, and then as a final step increasing the vacuum on the tobacco sufficiently to cause evaporation of some of the moisture supplied to the tobacco by the steam, whereby no perceptible change of color of the tobacco takes place, the tobacco being maintained at sub-atmospheric pressure throughout the process.
14. A process for increasing the moisture con-

- tent of tobacco comprising subjecting the tobacco to a high vacuum, then reducing the vacuum on the tobacco while supplying sufficient steam thereto to heat the tobacco to a temperature at 5 which heat deterioration thereof would take place after a time interval, and then prior to the expiration of such interval increasing the vacuum on the tobacco sufficiently to cause evaporation of some of the moisture supplied to the 10 tobacco by the steam, whereby the tobacco is cooled by such evaporation to a temperature at which heat deterioration thereof cannot take place.
15. A process for increasing the moisture content of a mass of tobacco comprising subjecting the tobacco to a high vacuum, then supplying steam to the tobacco while reducing the vacuum thereon to a sub-atmospheric pressure sufficiently in excess of the initial high vacuum to cause 20 penetration of the steam throughout the tobacco mass, whereby the tobacco is heated to a temperature at which heat deterioration thereof would take place after a time interval, and then prior to the expiration of such interval increasing the 25 vacuum on the tobacco sufficiently to cause evaporation of such a part of the moisture supplied to the tobacco by the steam that the tobacco temperature is reduced by such evaporation to a value at which heat deterioration of the 30 tobacco cannot take place.
16. A process for moistening tobacco which comprises first subjecting the tobacco to a vacuum of at least 28 inches of mercury, then reducing the vacuum while supplying to the tobacco an amount of steam sufficient to increase the moisture content of the tobacco by an amount in excess of the final increase desired, and then increasing the vacuum on the tobacco to a value lower than 28 inches of mercury until the excess moisture is evaporated and the temperature of the tobacco is reduced to at least 125° F.
- 40 17. A process for increasing the moisture content of tobacco comprising subjecting the tobacco to a high vacuum, then reducing the vac-
- uum on the tobacco while supplying sufficient steam thereto to heat the tobacco to a temperature at which heat deterioration thereof would take place after a given time interval, and then prior to the expiration of such interval increasing the vacuum on the tobacco sufficiently to cause evaporation of some of the moisture supplied to the tobacco by the steam, whereby the tobacco is cooled by such evaporation to a temperature at which heat deterioration thereof can 5 not take place within an interval appreciably greater than said given time interval.
18. A process for increasing the moisture content of a mass of tobacco comprising subjecting the tobacco to a high vacuum, then supplying steam to the tobacco while reducing the vacuum thereon to a sub-atmospheric pressure sufficiently in excess of the initial high vacuum to cause 10 penetration of the steam throughout the tobacco mass, whereby the tobacco is heated to a temperature at which heat deterioration thereof would take place after a given time interval, and then prior to the expiration of such interval increasing the vacuum on the tobacco sufficiently 15 to cause evaporation of such a part of the moisture supplied to the tobacco by the steam that the tobacco temperature is reduced by such evaporation to a value at which heat deterioration of the tobacco cannot take place within an interval 20 appreciably greater than said given time interval.
19. A process for exterminating organisms in tobacco comprising subjecting the tobacco to a high vacuum, supplying steam to the tobacco while reducing the vacuum thereon whereby the tobacco is heated to a temperature at which heat 25 deterioration would take place after a given time interval, and as a final step, prior to the expiration of such interval, increasing the vacuum on the tobacco to a value such that its temperature is reduced below that at which heat deterioration 30 can take place within an interval appreciably greater than said given time interval.
